(57) **CLAIM**

The ornamental design for a bottle, as shown and described.

DESCRIPTION

FIG. 1 is a front perspective view of the bottle.

FIG. 2 is a front elevational view of the bottle.

FIG. 3 is a right side elevational view thereof, the left side elevational view being a mirror image;

FIG. 4 is a top plan view of the bottle; and,

FIG. 5 is a bottom plan view of the bottle.

The left side of the bottle is symmetrical with the right side shown in FIG. 3.

The ornamental design which is claimed is shown in solid lines in the drawings. The broken lines in the drawings are for illustrative purposes only and form no part of the claimed design.
